(57) **CLAIM**

The ornamental design for a slide for a slide fastener, as shown and described.

DESCRIPTION

FIG. 1 is a perspective view of the top, front and right side of a slide for a slide fastener showing my (our) new design;
FIG. 2 is a front view thereof;
FIG. 3 is a rear view thereof;
FIG. 4 is a right side view thereof;
FIG. 5 is a left side view thereof;
FIG. 6 is a top plan view thereof;
FIG. 7 is a bottom view thereof;
FIG. 8 is a cross-sectional view at line 8-8 shown in FIG. 7;
FIG. 9 is a reference view of usage; and,
FIG. 10 is a reference view of usage.
The portions of the article in broken lines are shown for illustrative purposes only and form no part of the claimed design.
